UNITED STATES PATENT OFFICE.

CHARLES FRANKLIN COUVE, OF AURORA, ILLINOIS.

WATER-LIFT.

1,221,837.

Specification of Letters Patent. Patented Apr. 10, 1917.

Application filed August 5, 1915. Serial No. 43,791.

To all whom it may concern:

Be it known that I, CHARLES F. COUVE, a citizen of the United States, and a resident of Aurora, in the county of Kane and State 5 of Illinois, have invented a new and Improved Water-Lift, of which the following is a full, clear, and exact description.

My invention relates to means for raising water and comprehends an improved water 10 lift operated mechanically for the purpose of raising water from wells of considerable depth.

I seek to produce an apparatus of the type just mentioned and having the various parts 15 so arranged as to present a minimum of liability to get out of order and particularly while working under considerable pressures.

My apparatus consists of two main parts, 20 one of which I designate as a controller and the other as a pneumatically operated pump. The controller is placed above the ground and comprises a plurality of cylinders containing floats which are lifted alternately by 25 their buoyancy and the action of a liquid which rises and falls under pneumatic control; also a pneumatic valve for controlling the air supply and shifting the float thereof and mechanism controllable by means of 30 the float for actuating the pneumatic valve. The pump, which is placed in a well or the like, is operated by pressure of air from the controller, and raises the water from the well.

Reference is made to the accompanying drawings forming a part of this specification and in which like letters indicate like parts.

Figure 1 is a front view of the controller 40 mechanism, the pneumatic valve appearing in section and the other parts in elevation;

Fig. 2 is a section on the line 2—2 of Fig. 1, looking in the direction of the arrows;

Fig. 3 is a fragmentary section showing the upper portion of the pump mechanism which is disposed within the well casing;

Fig. 4 is a fragmentary view, partly in section, and partly in elevation, showing the 50 lower portion of the pump mechanism, which is located in the well casing;

Fig. 5 is a section on the line 5—5 of Fig. 3, looking in the direction of the arrows;

Fig. 6 is a section on the line 6—6 of 55 Fig. 3, looking in the direction of the arrows;

Fig. 7 is a section on the line 7—7 of Fig. 3, looking in the direction of the arrows;

Fig. 8 is a section on the line 8—8 of Fig. 4, looking in the direction of the ar- 60 rows;

Fig. 9 is a section on the line 9—9 of Fig. 4, looking in the direction of the arrows;

Fig. 10 is a vertical section showing both the controller mechanism and the pump; 65 and

Fig. 11 is a perspective view of the valve shutter.

I will first describe the controller mechanism, as shown in Figs. 1 and 2. A top 70 plate appears at 13, a bottom plate at 14, and a number of tie rods 15 extending from the top plate to the bottom plate, these parts thus constituting a framework. The tie rods are secured by nuts 16. The top plate 75 13 serves as a platform upon which various parts are mounted. Extending upwardly from this platform and secured thereto is a standard 17 which, because of its position, I designate as a middle standard. Located 80 upon opposite sides of the middle standard are two side standards 18, each of which is provided with a horizontally disposed portion 19 serving as a guide. Two large metallic cylinders are shown at 20 and 21 85 and are located between the top plate 13 and the bottom plate 14. Guide rods 22, 23 extend through the top plate 13 and into the cylinders 20 and 21. These guide rods also extend through the horizontally disposed 90 portions 19 of the side standards 18, and are adapted to be moved vertically. The guide rod 22 carries a pin 24, and the guide rod 23 carries a pin 25. The guide rod 22 is mounted upon a float 26 and movable therewith. Similarly, the guide rod 23 is mounted upon and is movable with a float 27.

Secured to the lower ends of the respective floats 26 and 27 are two guide rods 28, 29, and these guide rods carry baffle plates 30, 100 31. The cylinders 20, 21 are provided with partitions 32, 33, which are alike, the structure of the partition 33 being shown more particularly in Fig. 2. The partition 33 is provided with a dome 34 and with ports 35 105 extending through this dome. The partition 33 is further provided with a passage 36 extending into its wall and downwardly so as to communicate with the space below the partition. Extending downwardly from 110 the partitions 32 and 33 are two cylinders 37 and 38.

The weight of the controller mechanism rests upon legs 39. Supported rigidly upon the middle standard 17 is a member 40, which is the core of the main pneumatic valve. This core is provided with a number of portholes 41, 42, 43, 44, 45, 46, 47 and 48. A cap 49 is mounted upon the core 40 and covers the same. A valve shutter 50 engages the face of the core 40 and is partly cut away, as indicated in Fig. 1, in order to cover and uncover the various portholes as the valve shutter is rocked into different positions. For this purpose, a rocking shaft 51 is provided. This rocking shaft 15 has a square end 51^a which is secured rigidly to the valve shutter 50. Mounted rigidly upon the rocking shaft 51 is a rocking lever 52 carrying lugs 53, 54. A pair of hook levers 55, 56 are journaled upon the middle 20 standard 17 and provided with hooks 57, 58 for engaging the lugs 53, 54. Pivots connected with the respective hook levers 55, 56, and extending upwardly from the same are two links 59, 60, these links at their 25 upper ends being pivotally connected with two levers 61, 62, and these levers being journaled upon the respective standards 18. An air inlet pipe is shown at 63 and is connected rigidly with the core 40 in such a manner as 30 to communicate with the porthole 41 at all times, as may be understood from Fig. 2. A number of air pipes are shown at 64, 65, 66, 67, 68, 69, and these pipes communicate 35 respectively with the portholes 42, 43, 44, 46, 47 and 48. The porthole 45 is not connected with any of these pipes but communicates directly with the atmosphere as may be understood from Fig. 2. Two valve chests 40, 71, exactly alike, are mounted adjacent the upper end of the cylinders 20 and 21. The internal construction of the valve chest 71 is shown at the right of Fig. 2. A throttle piston 72 is movably mounted within this valve chest and a boss 73 serves as a limiting 45 stop for preventing excessive upward travel of the piston. The pipe 64 communicates with the valve chest 71 through a port 74. Two other pipes 75, 76 communicate directly with the valve chest, as shown more particularly in Figs. 1 and 2. The valve chest 71 is provided with a passage 76^a for equalizing air pressure above and below the throttle piston 72 under certain conditions, as hereinafter described. The pipe 75 is provided 50 with a hand valve 77 for regulating the speed at which the controller works. The pipe 75 is connected with a T 78 and extending below this T is a pipe 79 which leads downward to the partition 33 and communicates with the port 36. The pipes 76 and 65 are connected to a T 80^a and extending downwardly from this T is a pipe 80, the latter extending a distance into the well and serving as one of the air pipes thereof. A 60 similar air pipe 81 is connected with the

valve chest 70 by a pipe 82 and a T 82^a. A pipe 83 is connected with the valve chest 70 and is provided with a hand valve 84. This pipe is connected with a T 85, the latter being in communication with the air pipe 67. A pipe 86 is connected with the T 85 and extends downwardly from it to the partition 32 where its connection is analogous to that between the pipe 79 and the partition 33, as shown in Fig. 2. The well casing is shown 75 at 87 and may be of very great length as this apparatus is sometimes used in wells of very great depth. Located within the well casing 87 is a well cylinder 88, the upper end of which carries a head 89. This head is 80 provided with a collar 90 into which fits a pipe 91. This pipe is the water discharge pipe of the well—that is, the water main through which the water is raised from the well. Loosely mounted within the well cylinder 88 is a float 92, a cross section of which may be seen in Fig. 5. This float is 85 provided with a cylindrical inner wall 92^a and is further provided with a pair of guide grooves 93 through which the air pipes 80 and 81 extend. By this arrangement the hollow float 92 is always guided and maintained in proper position befitting its use. Secured rigidly upon the lower end of the water discharge pipe 91 is a valve fixture 95 94 provided with a valve chamber 95. Secured rigidly to the valve fixture 94 and extending across the valve chamber 95 is a bridge 96. A passage 97 communicates with the valve chamber 95, and the valve fixture 100 94 contains another passage 98, which, however, is not directly connected with either the valve chamber 95 or the passage 97. The float 92 tends to rest upon the upper end of the valve fixture 94, so as to close the upper 105 end of the passage 98. The passages 97 and 98 have each, in cross section, a substantially semi-cylindrical form, as may be understood from Fig. 6. The valve fixture 110 94 carries a removable valve seat 99 of substantially annular form, and also a removable guide 100 and a removable bushing 101. The three parts last mentioned are rendered removable in order to facilitate assembling 115 of the various parts and also for replacing them when worn out. Owing to the presence of the passages 97, 98 and the valve chamber 95, the middle portion of the valve fixture 120 94 is cut away so as to leave a skeleton member 102, as indicated in Fig. 3. A check valve 103 is located within the valve chamber 95 and is provided with a stem 104, the latter extending through the bridge 96 and also engaging and being guided by the guide 100. Secured rigidly to the bushing 101 125 and extending downwardly therefrom is a pipe 105, which may for most purposes be considered as practically a continuation of the pipe 91, that is to say, the pipe 105 is virtually part of the water discharge pipe. 130

A cylinder 106 is secured upon the lower end of the valve fixture 94 and located within a concentric tube of the well cylinder 88. A hollow float 107 adapted to serve as a valve member is located within the cylinder 106. Secured rigidly to the lower end of the water pipe 105 is a valve fixture 108 which is provided with a valve chamber 109. A valve seat 110 is removably mounted within the valve fixture 108. A check valve 111 is located within one valve chamber 109 and is provided with a valve stem 112. This valve stem extends through a bridge 113 and also engages the lower middle portion of the valve fixture 108. The check valve 111 is adapted to open and close a passage 115. The general form of the valve fixture 108 may be understood from Fig. 7. Located below the valve fixture 108 and secured to the lower end of the well cylinder 88 is another valve fixture 116. This valve fixture carries a spider 117 and a check valve 118, which is guided and held in position by this spider. The valve fixture 116 is provided with a valve chamber 119 and mounted within the latter is a check valve 120. The valve fixture 116 is further provided with a passage 121 of the form shown in Fig. 3. A spider 122 is mounted within the lower end of the valve fixture 116 and serves as a guide for the stem of the check valve 120. The valve chamber 119 communicates with a port 123, the latter being in communication with the space between the cylinders 88 and 106. The check valve 118 opens and closes a passage 124 with which the valve fixture 116 is provided and which communicates with the passage 121. Secured to the lower end of the valve fixture 116 is a water pipe 125 which virtually forms another continuation of the discharge pipe or water main. This pipe 125 may be of considerable length and is shown partly at the bottom of Fig. 3 and partly at the top of Fig. 4, the mechanism appearing in Fig. 4 being below that shown in Fig. 3. The lower end of the pipe 125 is connected to a collar 126, the latter being carried by a head 127. This head closes the upper end of a cylinder 128. A hollow float is shown at 129 and is located within the cylinder 128. The air pipe 80 extends through the head 127 of the cylinder 128, as indicated in Fig. 4, and there terminates. The air pipe 81, however, extends farther downward, as may be understood from Fig. 4. Below the float 129 is a valve fixture 130 which is provided with a small passage 131 extending through it from top to bottom. The valve fixture 130 is provided with an inlet port 132 through which the water of the well may enter. The valve fixture is further provided with a passage 133 and with a check valve 134 for controlling communication between the passage 133 and the port 132. The valve fixture 130 is also provided with a passage 135 serving to some extent as a valve chamber, and located within this passage is a valve member 136 carried by a valve stem 139. A valve seat 137 having an annular form is removably mounted within the valve fixture 130 between the passage 133 and the port 132. A check valve 134 normally rests upon this valve seat. A passage 137^a communicates with vertically disposed passages 138, the latter leading upwardly to the passage 135, as may be understood from Fig. 8. Mounted rigidly upon the lower end of the valve fixture 130 is a cylinder 140. Located within this cylinder and concentric with the same is a pipe 141 which is also secured to the lower end of the valve fixture 130. A hollow float 152, having the general form of a cylinder and also having a function as a valve, is located within the cylinder 140 and encircles the pipe 141. Secured to the lower end of the cylinder 140 is an inlet head 142 which carries a spider 143. A check valve 144 guided by this spider is carried by the head 142 and is adapted to open and close a passage 145 through its head. A valve fixture 146 is connected by a thread 147 with the lower end of the water pipe section 141. The valve fixture 146 is provided with a number of passages 148 of a form which may be readily understood from Fig. 9. These passages 148 communicate with a passage 149, the latter having substantially a disk shape. A check valve 150 controls communication between the passage 149 and a passage 151, the latter communicating directly with the lower end of the pipe section 141.

It will be noticed that the air pipes 80 and 81 extend to different distances into the well, as may be understood from Fig. 4. The air pipe 80 terminates at the upper end of the cylinder 128, while the air pipe 81 extends into engagement with the valve fixture 130 and communicates with the passage 131. In all wells, whether deep or shallow, the parts shown in Fig. 4 are employed, but in shallow wells the mechanism shown in Fig. 3 is not essential. For very deep wells the mechanism appearing in Fig. 3 may be duplicated, that is, two or more sets of this mechanism may be arranged one over the other.

Within each of the cylinders 20, 21, used above ground and forming parts of the tubular mechanism, I have placed a quantity of a non-freezing liquid, preferably alcohol. This liquid is to all intents and purposes a part of the operating mechanism of the controller and has nothing to do with the water or other liquid to be raised from the well.

I will now describe the action of the controller mechanism: The air inlet pipe 63 being connected with a suitable source of compressed air, the hand valves 77 and 84

are turned so as to be opened wholly or partially, depending upon the speed at which the controller is to be operated. Assuming that at the starting, the movable parts are 5 in the respective positions indicated for them in Figs. 1 and 2, I will trace the cycle of operations which will now take place: Owing to the engagement of the hook 58 with the lug 54 and the consequent position 10 assumed by the movable valve shutter 50, the portholes 41 and 48 now communicate with each other; the portholes 42, 46 and 47 are closed; and the portholes 44 and 43 are in communication with the porthole 45, which 15 in turn is in open communication with the atmosphere; therefore, the pipes 65 and 66 virtually communicate with the atmosphere, whereas the air flowing in through the pipe 63 passes freely into the pipe 69 and thus 20 into the valve chest 70 where it raises the valve piston 72 and passes downwardly through the pipes 81 and 86. The air thus discharged from the pipe 86 passes into the lower end of the cylinder 20 where it accumulates between the cylinder 37 and the 25 lower portion of the cylinder 20. It, therefore, displaces most of the non-freezing liquid which is thus pressed upwardly through the cylinder 37 and ports corresponding to the ports 35, shown in Fig. 2, 30 the liquid flowing upwardly against the baffle plate 30 and finding its way around this plate to accumulate above the partition 32, and as it rises in depth the float 26 is 35 lifted. The raising of the float 26 causes the guide rod 22 to move bodily upward and this motion is continued until the pin 24 engages the adjacent end of the lever 62. This done, the link 60, by pulling upwardly 40 upon the hook lever 56, disengages the hook 58 from the lug 54. This leaves the rocking lever 52 free to rock in a clockwise direction according to Fig. 1, and this rocking 45 movement is accomplished by the descent of the float 27 within the cylinder 21 and the consequent lowering of the guide rod 23 so as to swing the pin 25 against the adjacent portion of the rocking lever 52. The descent of the float 27, causing this movement, is 50 due to the fact that the non-freezing liquid located above the partition 33 now flows downwardly, below this partition, and downwardly through the tube 38, so that the level of the liquid inside and outside of the cylinder 38 tends to equalize. The reason why 55 this movement of the liquid takes place is that the air, heretofore located between the cylinders 38 and 21, and below the partition 33, is now free to escape upwardly through the pipes 79, 66 and the portholes 44 and 45, into the atmosphere.

As the air flows downwardly through the pipe 81 and into the well, air is also pressing upwardly from the well through the pipe 80. This air does not pass through the throttle 65

valve chest 71 for the reason that the valve piston is now in its lowermost position and consequently exhaust air coming up from the well is merely bypassed from the well cylinder through the pipe 65.

70

Air exhausts very quickly from the controller after the liquid which is being raised has been elevated sufficiently to cause the rocking lever 52 to be tripped, thus allowing the float 26 (or 27 as the case may be) to drop abruptly, so as to carry with it the rocking lever 52.

75

Whenever the piston within the throttle valve chest 71 is up, the piston in the throttle valve chest 70 is down, and air is exhausting from the pipe 81 through the T 82^a into the pipe 68, thence through the port 47 of the main valve to the port 45, from which it makes its escape directly into the atmosphere.

80

Whenever the controlling cylinder is exhausting, air passes from the pipe 86 into the T 85, whence it flows into the pipe 67 to port 46 and from this port to the port 45, whence it escapes into the atmosphere.

85

The throttle mechanism is so arranged as to stop the action of the controller whenever the flow of water is shut off by action of the end valves used for this purpose. When the flow of water is thus shut off, the air pressure within the well cylinders becomes the same as the air pressure in the pipes 69 and 64, the air pressure being thus equalized, the throttle pistons drop to the lower limit of their travel, and the air pressure upon the piston becomes equalized owing to the action of the port 76^a. Whenever the throttle pistons are down the flow of air to the controller is thereby stopped.

90

Whenever air escapes from the pipe 81, 105 it also escapes from the pipe 86 for the reason that whenever the porthole 46 is open, the porthole 47 is also open. There are always two ports in communication with the port 45. Whenever the float 27 ascends and reaches an elevation sufficiently high to bring the pin 25 into engagement with the lever 61, the hook 57 is raised until it is disengaged from the lug 53 on the rocking lever 52. This allows the float 26 to drop 110 abruptly.

110

By analogous action of the parts, when the float 26 ascends, it ultimately causes the float 27 to drop abruptly.

115

I will now describe the action of the pump—that is, the mechanism located below the upper surface of the earth. The water enters at the bottom through the opening 145 and also through the opening 132, which is located some distance above the bottom. I will assume that there is no air below the surface of the water and that the upper level of the water may be at any point above the opening 132.

120

Suppose next air is passing downwardly 130

through the pipe 81. A portion of this air enters the cylinder 88, being discharged through the opening 81^a in the pipe 81. The water contained in the cylinder 88 causes the float valve 92 to clear the aperture 98. The pressure of air admitted into the upper portion of the cylinder 88 causes the water contained within this cylinder to pass through the passage 98 and upwardly past the check valve 103 into the discharge pipe 91, which it follows upwardly to the surface of the earth and is then discharged. A portion of the air passing downwardly through the air pipe is fed to the valve fixture 130 and passes through the port 131 thereof into the upper portion of the cylinder 140. This air being under considerable pressure displaces the water contained within the cylinder 140 and causes it to pass downwardly through the passage 148, then through the passage 149 and upwardly past the check valve 150, and then through the passage 151 into the discharge pipe section 141. From here the water passes into the passage section 137^a, then upwardly through the passage 138 (see Fig. 8), then over the check valve 136 without disturbing this valve, and through the passage 135 into the discharge pipe section 125. The water travels upwardly through the spider 122 to the valve fixture 108, passing downwardly through the passage 114 and upwardly through the passage 115 and it lifts the check valve 111 and passes upwardly into the discharge pipe section 105.

Suppose now that the action of the controller be reversed as above described, so much so that air is forced downwardly through the pipe 80 instead of the air pipe 81. A portion of the air thus passing downwardly the pipe 80 is discharged through the port 80^a into the upper portion of the cylinder 106, and another portion of the air is discharged from the lower end of the air pipe 80 into the upper portion of the cylinder 128. A portion of the air enters the upper end of the cylinder 106 and the water contained within this cylinder is displaced by the air and passes downwardly through the passage 114 then upwardly through its passage 115, past the check valve 111, through the passage 109 and into the discharge pipe section 105. Thence the water passes through the passage 97, valve chamber 95, into the upper portion of the discharge pipe 91 which leads up to the surface of the earth, as elsewhere described. The displacement of water within the cylinder 128, due to the entrance of air thereto from the lower end of the air pipe 80, causes the water to pass from the cylinder 128 downwardly through the passage 133, then upwardly past the check valve 136, through the passage 135 and into the discharge pipe section 125, thence the water passes the spider 122 and goes through the passages 121 and

124 into the cylinder 106, thence it follows the passages 114 and 115 and 109 into the pipe section 105. From here it goes through the passage 97 and 95 into the discharge pipe 91 whence it makes its escape. If there be in the well an accumulation of water having sufficient pressure to raise the check valve 134, the water enters the opening 132 into the passage 133 and thence passes upwardly into the cylinder 128. Also at the bottom of the well the water enters through the opening 145, passing by the check valve 144. Water thus flows into the well at two points and this may take place either while the controller is in action or while it is idle, the difference being that when the water flows in during the operation of the controller the flow is intermittent.

The floats 107, 92, 129 and 152 are emergency floats. Their purpose is to close the water discharging pipes in order to prevent air from flowing through the same as might otherwise take place in instances where the controller has been adjusted to operate very slowly. The floats in question descend as water is pressed out and in descending they close the ports 114, 148, 98 and 133.

These floats are not absolutely essential and are only recommended for pumps which are operated by inexperienced workmen.

After each displacement of water made by the air as above described, the air used for the displacement passes upwardly, through the air pipe 80 or 81, as the case may be, and makes its escape through the port 45 of the main valve of the controller to enter the atmosphere.

The pipe section 125 may be of any desired length commensurate with the depth of the well.

I do not limit myself to the precise construction shown, as variation may be made therefrom without departing from the spirit of my invention.

Having thus described my invention, I claim as new and desire to secure by Letters Patent:

1. In a water lifter, the combination of a pneumatic pump to be located in a well, and mechanism located above the surface of the earth for supplying compressed air alternately to different portions of said pump, so that one portion is discharging while another portion is being filled with water, the said mechanism including a plurality of cylinders, floats within said cylinders, a pneumatic valve for controlling the air supply and shifting the floats alternately, a rocking shaft connected with said valve for actuating the same, a rocking lever connected rigidly to said rocking shaft, hook levers for holding the rocking lever in different positions, and connections from each of said floats to one of said hook levers and to the rocking lever for actuating said valve.

2. In a controlling apparatus for operating a water lift, the combination of a valve core provided with a number of ports, one of said ports being an inlet port and another being a discharge port, a shutter engaging said core and adapted to open and close some of said ports without interfering with the action of said inlet port and said discharge port, a rocking shaft connected with 10 said shutter for actuating the same, a rocking lever connected rigidly to said rocking shaft and provided with lugs, hook levers provided with hooks for engaging said lugs in order to hold said rocking lever in different positions, a plurality of float mechanisms, connections from each of said float mechanisms to one of said hook levers and to one end of 15 said rocking lever for the purpose of enabling said float mechanisms to control the 20 rocking of said rocking lever and said shutter, throttle valves connected pneumatically to said stationary core and communicating with said ports thereof, said throttle valves being controllable by air passing through 25 some of said ports, and air pipes connected with said throttle valves and extending into a well for the purpose of displacing water therein.

3. A controller for operating water lifts 30 comprising a stationary core provided with a number of ports, one of said ports being an inlet port and another an exhaust port, a pipe for supplying air to said inlet port, a shutter engaging said stationary core and 35 movable relatively thereto, said shutter having such form as to control the opening and closing of some of said ports when said shutter is moved into different positions, a rocking shaft connected with said shutter, a 40 rocking lever connected with the said shaft, hook levers for engaging the rocking lever to hold the same in different positions, and float mechanisms including vertically movable guide rods for controlling the hook 45 levers and the rocking lever, valve chests, connections from some of said ports to some of said valve chests, sliding valves mounted within said valve chests, and an air pipe connected with each of said valve chests and 50 extending into a well, said air pipes being controllable by said sliding valves within said valve chests.

4. In a controlling mechanism of the character described, the combination of a pneumatic valve, a rocking lever for actuating 55 said valve, a cylinder, a float mounted within said cylinder, connections from said float to said rocking lever for enabling movements of the float to actuate said valve, a 60 partition mounted within said cylinder and provided with ports, a second cylinder smaller than said first mentioned cylinder mounted upon said partition and extending downwardly therefrom, means controllable 65 by said valve for discharging air into said

first mentioned cylinder at a point below said partition so as to displace a liquid therein contained and to cause said liquid to pass through said second mentioned cylinder and said ports, a float mounted within said first 70 mentioned cylinder and controllable by said liquid, and connections from said float to said valve.

5. In a pump, the combination of a well casing, a longitudinal member mounted 75 therein and having the general form of a cylinder, said longitudinal member being divided into compartments, valve fixtures located within said longitudinal member and normally separating said compartments, 80 means for admitting a liquid into the different compartments of said longitudinal member, air pipes extending downward within the cylinder and having ports in their walls opening into some of said compartments, the terminals of said pipes leading to other compartments, the terminal of one of the air pipes opening into the upper part of a compartment, and the terminal of the other air pipe extending downward below the terminal of the first mentioned air pipe and communicating through a port in one of said valve fixtures with another compartment, and mechanism for alternately admitting charges of air through said pipes 85 into some of the compartments in order to displace charges of water from said compartments.

6. In a pump, the combination of a well casing, a longitudinal member mounted 100 within said well casing and provided with a plurality of compartments, valve fixtures carried by said longitudinal member and provided with valves controlling communication between said compartments thereof, 105 means for admitting a liquid into two of said compartments, one of said valve fixtures having a port leading therethrough and communicating with one of the last mentioned compartments, an air pipe having 110 its terminal connected with said port to admit air to said compartment, an air pipe having its terminal leading to the other of said last mentioned compartments, and mechanism for applying air pressure to said 115 pipes for displacing alternately the volumes of water contained respectively within said last mentioned compartments.

7. In a pump, the combination of a well casing, a longitudinal member mounted 120 therein and provided with a plurality of compartments, valve fixtures carried by said longitudinal member, and provided with valves controlling communication from one of said compartments to another, air inlet 125 pipes located within said longitudinal member and each provided with a discharge port and a discharge terminal for discharging air into a plurality of said compartments simultaneously in order to displace water 130

therefrom, one of said valve fixtures having a port leading therethrough, the terminal of one of said pipes being connected with said valve fixture and communicating through 5 said port, with the compartment, and mechanism for applying air pressure to said air inlet pipes one at a time in a different order of succession.

8. In a pump, the combination of a well 10 casing, a cylindrical member mounted within the well casing and provided with a plurality of compartments, valve fixtures carried by said cylindrical member and provided with valves controlling communication 15 from one of said compartments to another, air inlet pipes located within said cylindrical member and each provided with a discharge port, and a discharge terminal for discharging air into a plurality of said 20 compartments simultaneously in order to displace water therefrom, water discharge pipe sections connected with the valve fixtures, one of said valve fixtures having a passage leading therethrough, the terminal 25 of one of said air pipes being connected with the upper end of said passage and communicating through the said passage with a compartment, the said valve fixture being provided with an inlet port through which 30 the water of the well may enter.

9. In a pump, the combination of a cylindrical member to be mounted within a well casing, a valve fixture mounted within said cylindrical member and provided with a 35 valve chamber and with passages communicating with said valve chamber, a check valve mounted within said valve chamber, a valve seat of substantially annular form removably mounted within said valve fixture 40 and adapted to be engaged by said valve, a guide member below the valve seat detachably connected with said valve fixture and provided with means for guiding said valve, a removable bushing in the valve fixture be-

low the said guide member, and a discharge 45 pipe section secured to the bushing and extending downwardly therefrom.

10. In a pump, the combination of a cylinder, a pair of air inlet pipes located within said cylinder, a discharge water pipe section located within said cylinder and concentric relatively to the cylinder, and a float having a substantially cylindrical form, said float encircling said discharge pipe and being provided with grooves through which 55 said air inlet pipes extend in order to enable said air inlet pipes to guide said float.

11. In a pump, the combination of a cylinder, a pair of air inlet pipes located within said cylinder, a discharge water pipe section located within said cylinder, a valve fixture connected with said pipe section and through which the water passes to the discharge pipe section, a float encircling said discharge pipe section and having guided 60 movement on the said air inlet pipes, the said float forming a controlling valve for the said valve fixture.

12. In a device of the character described, the combination of a cylinder, means for 70 forcing water through said cylinder, a valve fixture mounted within said cylinder and provided with a number of passages located parallel with each other, said valve fixture being further provided with a single passage 75 into which the lower ends of all of said first mentioned passages merge, and a check valve carried by said valve fixture above said mentioned passage for opening and closing communication therewith.

In testimony whereof I have signed my name to this specification in the presence of two subscribing witnesses.

CHARLES FRANKLIN COUVE.
